UNITED STATES PATENT OFFICE.

HUGH DE HAVEN, OF NEW YORK, N. Y.

TYING DEVICE.

1,149,994

Specification of Letters Patent. Patented Aug. 10, 1915.

Application filed February 17, 1915. Serial No. 8,968.

To all whom it may concern:

Be it known that I, HUGH DE HAVEN, a citizen of the United States, and a resident of the city of New York, borough of Brooklyn, in the county of Kings and State of New York, have invented a new and Improved Tying Device, of which the following is a full, clear, and exact description.

The invention relates to ties or bands tied around packages, packing boxes and other receptacles, and its object is to provide a new and improved tying device arranged to enable the operator to draw the band firmly around the article and to then securely fasten the ends together.

In order to accomplish the desired result, use is made of an angular holder adapted to fit onto an angular tying plate, the said holder having in one member an opening for the reception of the receiving end of the tying plate, and a clamping device mounted to swing outwardly on the other member of the holder to pull the band through the said receiving end thus drawing it tightly around the article.

A practical embodiment of the invention is represented in the accompanying drawings forming a part of this specification, in which similar characters of reference indicate corresponding parts in all the views.

Figure 1 is a sectional side elevation of the tying device as applied and with the clamping device in starting position, the section being on the line 1-1 of Fig. 2; Fig. 2 is a plan view of the same with the clamping device swung outward and with the band drawn taut around the article; Fig. 3 is a cross section of the tying device on the line 3-3 of Fig. 2 and showing more particularly the closing device for closing the tie plate; Fig. 4 is a sectional side elevation of the tie plate in position on the article and after the band has been tied; Fig. 5 is a perspective view of the tie plate; and Fig. 6 is a similar view of a modified form of tie plate for use in conjunction with a tying wire.

The tying device is more especially designed for use on a tying band A attached at one end to the vertical member of an angular tying plate B having its horizontal member B² formed with upwardly extending flanges B³, thus providing a guideway for the passage of the free end of the band A after the latter has been passed around

the package, packing box or other article C to be bound or tied. The support or holder D of the tying device is of angular shape fitting the angular tying plate B, as plainly indicated in the drawings, and the holder D is for this purpose provided with a vertical member D' and a horizontal member D² provided at or near its middle with an opening D³ for the passage of the member B² of the tying plate and its flanges B³. The vertical member D' of the holder D fits against the outside of the vertical member B' of the tying plate B while the horizontal member D² of the holder D rests on top of the article C when using the device for drawing the band A tightly around the article C. The member D' of the holder D is provided with spaced lugs D⁴ supporting a pivot E on which is mounted to swing in an outward and downward direction an arm F terminating in a jaw F' operating in conjunction with a jaw F² for clamping the free end of the band A between the said jaws, as plainly shown in Figs. 1 and 2. The jaw F² is a movable jaw and is pivotally connected at F³ to the arm F, and on the jaw F² is arranged a handle F⁴ under the control of the operator for swinging the jaw F² into closed or open position and also to swing the arm F outward and downward when tying the band A around the article C, that is, on swinging the arm F from the position shown in full lines in Fig. 1 to that shown in dotted lines in the said Fig. 1 and in full lines in Fig. 2.

The tying device is used as follows: The tying plate B is placed in position on one corner of the article C and then the band A is passed around the article and passed between the flanges B³ of the horizontal member B² of the tying plate B. The operator now places the tying device in position on the tying plate B, as plainly indicated in Figs. 1, 2 and 3, and then the arm F is swung into vertical position and the jaw F² is opened to permit of passing the free end of the band A across the top of the jaw F', after which the jaw F² is closed to firmly clamp the free end between the jaws F' and F². The operator having hold of the handle F⁴ now swings the arm F with the closed jaws outward and downward so that a pull is exerted on the free end of the band A to draw the same tightly around the article C. If the band has been drawn sufficiently tight

at the first operation the flanges B^3 are closed down upon the band A, and then the terminal of the band A is released by opening the jaw F^2 and the terminal is bent back over the closed flanges B^3 , as plainly indicated in Fig. 4. In order to enable the operator to readily close the flanges B^3 as above described, use is preferably made of a closing lever G fulcrumed on the top of the member D^2 and adapted to swing in a transverse direction. The lever G is provided with a die G' adapted to engage the flanges B^3 so as to press the same downward on swinging the lever G down into closing position, as will be readily understood by reference to Fig. 3. It is understood that during the time the closing lever G is used the band A is held taut by the jaws F' , F^2 , and after the flanges B^3 have been closed down upon the band A, the jaw F^2 is opened and the terminal of the band is bent back over the closed flanges B^3 , as previously explained and shown in Fig. 4.

In case the band is not drawn sufficiently tight around the article C during the first operation as above described, then the jaw F^2 is opened and the arm F is swung back into vertical position, after which the jaw F^2 is closed to take another grip on the band A and to again draw the same taut on swinging the arm F downward. This operation can be repeated as many times as necessary to draw the band A very tight around the article C and then the flanges B^3 are closed as before explained. After the terminal has been bent over the flanges B^3 the surplus material is cut off (see Fig. 4).

In case a tying plate H is used in conjunction with a tying wire I, then one end of this wire I is attached to an eye H^2 in the vertical member H' of the said tie plate, while the other end of the wire is passed through an eye H^4 in the horizontal member H^2 of the tying plate H. The free end of the wire passing through the eye H^4 is engaged between the jaws F and F' to allow of drawing the wire taut around the article C, the same as above described relative to the band A, and then the terminal of the wire is bent over the eye H^4 (see dotted lines in Fig. 6); and is firmly pressed down in contact with the eye by the use of the lever G and its die G' .

The tying device shown and described is very simple and durable in construction and can be readily applied and manipulated for drawing the band A or the wire I tightly around the article C and then fastening the free end of the band or wire in place on the corresponding tying plate B or H.

By reference to Fig. 1 it will be noticed that the jaw F is approximately on a level with the top of the member B^2 of the tying plate B at the time the arm F is in vertical

position so that the terminal of the band A can be readily clamped in position on the jaw F' by the jaw F^2 .

The flanges B^3 are preferably provided on their inner faces with struck-up projections adapted to take a firm hold of the band A when pressed in contact with the same to allow of cutting off the band intermediate the tying plate B and the jaws F' , F^2 to allow of bending the band end back over the flanges B^3 and without danger of the band slipping in the tying plate.

Having thus described my invention, I claim as new and desire to secure by Letters Patent:

1. A tying device for use on a band attached at one end to a tying plate, comprising an angular holder adapted to fit onto an angular tying plate and having in one member an opening for the reception of the receiving end of the tying plate, and a clamping device mounted to swing outwardly on the other member of the holder to pull the band through the said receiving end.

2. A tying device for use on a band attached at one end to an angular tying plate, comprising an angular holder adapted to fit onto the tying plate and having one member provided with an opening for the reception of the receiving end of the tying plate, an arm mounted to swing outward on the other member of the holder and provided with a jaw, and a jaw lever fulcrumed on the said arm and having a jaw, the said jaws when closed being in alignment with the said opening and being adapted to clamp the free end of the band between the jaws, the said lever serving as a handle to swing the arm outward to draw the free end of the band through the receiving end of the tying plate.

3. A tying device for use on a band attached at one end to an angular tying plate, comprising an angular holder adapted to fit onto the tying plate and having one member provided with an opening for the reception of the receiving end of the tying plate, an arm mounted to swing outward on the other member of the holder and provided with a jaw, a jaw lever fulcrumed on the said arm and having a jaw, the said jaws when closed being in alignment with the said opening and being adapted to clamp the free end of the band between the jaws, the said lever serving as a handle to swing the arm outward to draw the free end of the band through the receiving end of the tying plate, and a closing device mounted on the holder and adapted to extend over the said opening to close the receiving end of the holder while the free end of the band is held taut by the said jaws.

4. A tying device for use on a band attached at one end to an angular tying plate

provided with a receiving end for the reception of the loose end of the band, comprising an angular holder fitting on the said tying plate and having an opening for the reception of the said receiving end of the tying plate, drawing means mounted on the said holder for drawing the free end of the band through the said receiving end, and closing means mounted on the said holder for closing the said receiving end of the tying plate.

5. A tying device for use on a band attached at one end to an angular tying plate, comprising an angular holder adapted to fit onto the tying plate and having one member provided with an opening for the reception of the receiving end of the tying plate, an arm mounted to swing outward on the other member of the holder and pro-

vided with a jaw, a jaw lever fulcrumed on the said arm and having a jaw, the said jaws when closed being in alinement with the said opening and being adapted to clamp the free end of the band between the jaws, the said lever serving as a handle to swing the arm outward to draw the free end of the band through the receiving end of the tying plate, and a hand lever mounted to swing on the slotted member of the holder and having a die adapted to engage the receiving end of the plate to close the said receiving end.

In testimony whereof I have signed my name to this specification in the presence of two subscribing witnesses.

HUGH DE HAVEN.
